UNITED STATES PATENT OFFICE.

ETHEL B. WILDE, OF PEORIA, ILLINOIS.

COVER FOR FUEL BURNERS.

Application filed April 15, 1925. Serial No. 23,188.

My invention relates to domestic oil burners, and more particularly to a special cover member for same. The object of the invention is in the provision of a cover that 5 completely surrounds the domestic fuel burner, with the result that mechanical noises are lessened and the possibility of accidents to persons, as well as the burner itself, are prevented.

Another object of the invention is in the provision of a removable cover member for a domestic fuel burner, said cover being fashioned in such manner as to lessen, to a considerable degree, the mechanical noises 15 of the burner.

Still another object of my invention is in the provision of a specially formed cover for domestic oil burners, the same being arranged to prevent unauthorized adjustment 20 or manipulation of the mechanism of the burner.

A further object of the invention is in the provision of a specially formed cover plate for a domestic oil burner, the same being related to the burner mechanism in an optionally locked relation, to prevent the unauthorized handling of the operating mechanism. 25

Other objects of the invention will appear in the following specification, taken in connection with the annexed drawings, in 30 which—

Fig. 1 is a plan view, from above, of the cover;

Fig. 2 is a front elevation;

Fig. 3 is an end elevation of the cover;

Fig. 4 is a detail showing of the mechanical adjustment aperture and locking means;

Fig. 5 is a detail of the attachment means between the cover and burner;

Fig. 6 is a detail showing of the means for locking the cover to the burner; and

Fig. 7 is an end elevation showing the general assembly of cover with the burner.

Referring to the figures, there is shown in 45 Figure 7 the general manner of relating and assembling the cover with the burner. The burner, referred to generally as 10, is one of the types of the well known class of domestic oil burners, the same having their main 50 use in domestic installations, where they are automatically controlled by a thermostat located in the dwelling to be heated. It is not considered necessary to describe in detail the fuel burning device, inasmuch as any 55 kind or type of burner might be covered in substantially the same manner as disclosed

by applicant, with, of course, minor mechanical and physical changes. It might also be said that the present cover member is designed for use entirely upon domestic oil 60 burners having their mechanical portions without the combustion chamber, the same usually standing directly in front of the furnace, although this construction is not 65 universally followed.

Domestic oil burners, of no matter what type, depend upon an electric motor for power, as well as various pumps and air blast means for the atomization of the fuel. It will be obvious that the movement of these 70 various parts causes considerable mechanical noise.

In order to obtain efficient atomization in domestic oil burners, due to the low temperature conditions, a considerable amount of 75 adjustment of the burner is necessary upon initial installation, and sometimes later. Unless covered, such adjustment members are liable of movement by other than the proper or authorized person. 80

Possibly the greatest factor to be regarded in a domestic oil burning device is that of safety, and the factor of safety is directly proportionate to the efficiency of atomization. Any improper and unauthorized handling of the adjustment mechanism of an ordinary domestic oil burner, unless by an experienced person, will result in the change of the fuel and air conditions, lower the efficiency of atomization and cause either an 90 accident or at least damage to the burner and combustion chamber assembly. Again, the fact that there are many electrical connections controlling the high voltage circuits prompted the applicant to devise a means 95 for protecting children and careless persons from thoughtless investigation and adjustment.

To overcome the above disadvantages of disposing the moving and operating portions 100 of a domestic fuel burner outside the combustion chamber, I have provided a cover member 12, fashioned of sheet steel (although this construction is not absolutely necessary), said cover being fashioned for 105 either a fireproof or noise-deadening lining, if thought necessary. The cover 12 in the present instance, is rectangular in shape, in view of the physical proportions of the present disclosed burner, and is fashioned to 110 completely house the burner. The cover rests upon the sump or base portion 13 of

said burner. An opening 14 in the cover permits the projection therethrough of the blast housing and fuel discharge tubes of the burner. A second screen covered opening 15 is disposed in one end of the cover and is adjacent a sirocco type of fan member that is common to almost all types of burner. The cover has one means of attachment to the burner, or rather the base portion thereof, in the projecting bolts 16 attached thereto, and lock nuts 17 which hold the cover securely attached to the base. A second means for attaching the cover to the burner is found in the screw member 18, which has its head portion 19 embedded in a flange 20, said flange being positively attached to the top of the cover, and defining the heart shaped aperture 21 therein. The lower end of the screw 18 is threaded into a bracket 22, securely attached, as at 23, to a portion of the burner. Pivoted as at 24 to the flange 20 is a small heart shaped plate 25, adapted to cover the adjustment aperture 21. This plate 25 has a hole 26 therein adapted to register with a similar hole 27 in the flange 20. The formal padlock 28 provides means for securely locking the plate 25 to the cover as well as locking the cover to the burner, in view of the fact that the movement of the plate 25 to a locked position covers the head portion 19 of the screw 18, said head portion being countersunk in the flange 20.

In view of the above description, the assembly, attachment and locking of the cover plate to the burner is thought obvious.

The sale of domestic oil burners has met with considerable resistance, due to the fact that they were noisy. The atomization of fuel and the combustion of same is attended

with a certain amount of noise, if any real heat is to be obtained. This combustion noise is housed by the furnace, and although noticeable to some degree, the fact that it is confined prevents its being heard to any considerable extent in the dwelling that is being heated. The mechanical portions, however, being disposed without the combustion chamber, and not being confined, add greatly, due to their movement, to the noise created in the combustion of the fuel. There is the hum of the electric motor, as well as the noise of the pumps and other elements, which seems to carry further into the dwelling than the noise of combustion. Applicant, after considerable thought and experiment, devised the present cover member for housing the burner in a compact and efficient manner. The result of the housing of the mechanical portions of the burner are so readily noticed that it is but necessary to raise the cover, and then to place it again over the burner, to realize that substantially half of the mechanical noises are obviated by its use.

What I claim is:

The combination with an oil burning device, of a cover member surrounding said oil burner in a manner to lesson the mechanical noises therefrom, said cover member having an adjustment aperture therein, a cover plate for said aperture, and means for simultaneously locking the plate upon the adjustment aperture as well as the cover to the burner.

In testimony whereof I have hereunto affixed my signature.

ETHEL B. WILDE.
